UNITED STATES PATENT OFFICE.

WILLIAM J. FRISBIE, OF CHICAGO, ILLINOIS, ASSIGNOR TO JUSTRITE MANUFACTURING COMPANY, OF CHICAGO, ILLINOIS, A CORPORATION OF ILLINOIS.

ACETYLENE LAMP.

1,424,464.

Specification of Letters Patent. Patented Aug. 1, 1922.

Application filed August 29, 1921. Serial No. 496,544.

To all whom it may concern:

Be it known that I, WILLIAM J. FRISBIE, a citizen of the United States, and a resident of Chicago, in the county of Cook, State of Illinois, have invented certain new and useful Improvements in Acetylene Lamps, of which the following is a specification.

My invention relates to acetylene lamps and particularly to miners' acetylene cap lamps. The general object of my invention is to provide improved supporting and strengthening seat structures for the detachable reflectors.

The reflectors on miners' cap lamps are constructed of comparatively thin sheet metal and are subjected to blows, bumps and strain during use in the mine, particularly when the miner taps them to stir up or loosen the carbide. The reflectors are therefore made readily detachable so that a bent or useless reflector can be readily removed and a new one applied. More in detail, the object of my invention is to provide a reflector which is of itself strengthened, and to provide a seat therefor on the lamp to which the reflector can be readily applied and which after receiving the reflector will further brace and strengthen it against bending or other injury during use of the lamp.

On the accompanying drawings I have shown a miner's cap lamp in which my invention is incorporated. On the drawings—

Fig. 1 is a front elevational view of the lamp,

Fig. 2 is a side elevational view,

Fig. 3 is a side elevational view of the front part of the lamp with the reflector and its supporting mechanism in section on plane 3—3, Fig. 1,

Fig. 4 is a front elevational view of a lamp showing a modified arrangement and

Fig. 5 is a side elevational view of the lamp with the reflector and its supporting structure in section on plane 5—5, Fig. 4.

The lamp shown comprises the cylindrical water container A and the carbide cup B. The bracket 10 and the hook 11 serve to support the lamp from the miner's cap. 12 represents a valve operating lever for controlling the valve for the water feed to the carbide. The generated gas escapes through the gas tube 13 extending diametrically out at one side of the water container, and sup-

porting in its end the gas tip 14. The reflector 15 is of the usual concave type provided at its center with the hole 16 for receiving the gas tube so that the issuing flame will extend axially with reference to the reflector.

In accordance with my invention I apply an annular reenforcing frame 17 on the back of the reflector concentric with its axis, which frame has the cylindrical flange 18 extending rearwardly therefrom and threaded on its exterior for engaging in the threaded annular spacing and bracing frame 19 secured to the water container concentric with the gas tube 13. As shown in Fig. 2, the rear edge of the frame 19 is shaped to intimately fit against the cylindrical wall of the water container and to receive the water container strengthening ridge a. The frame is preferably rigidly secured to the container wall as by means of soldering.

The diameter of the reflector strengthening frame 17 is such that it will strengthen the reflector at the point where it would be most inclined to bend under pressure, bumps, etc. The reflector is thus of itself efficiently strengthened and reenforced, and when it is screwed on to the spacing frame 19, this frame will abut against the frame 17 and further strengthen and brace the reflector against bending or crimping, and the reflector will at all times be rigidly held in its proper plane concentric with the gas tube 13. The opening 16 in the reflector is of sufficient diameter to readily clear the gas tube when the reflector is applied or removed. Should the reflector become damaged and useless, it can be readily unscrewed, and a new reflector applied.

In Figs. 4 and 5 I have shown a modified arrangement. The reflector 20 has the large central opening 21 concentric with the reflector axis from which the cylindrical flange 22 extends rearwardly and is threaded on its interior to receive the threaded end of the cylindrical spacing and seating frame 23 which is rigidly secured to the water container concentric with the gas tube 13. The front of the frame 23 is closed by the wall 24 which has the central opening 25 for receiving the gas tube, and this wall is concave on its outer side, its radius of curvature being that of the reflector and the concave surface forming a continuation of the re-

flector concave surface when the reflector is screwed into place on the frame 23. The flange 22 reenforces the reflector structure and the spacer frame 23 further strengthens 5 the reflector and braces it against bending.

I thus provide efficient supporting, strengthening and bracing structure for sheet metal reflectors on acetylene lamps which holds the reflector in proper position 10 and alinement and which prevents bending or distorting thereof during ordinary use of the lamp. The reflector can be readily applied or removed at any time. Changes and modifications are, of course, possible 15 which would still come within the scope of the invention and I do not therefore desire to be limited to the precise construction and arrangement shown and described. I claim as my invention:

20 1. The combination with a lamp body having a gas orifice, of a spacer frame intimately engaging with and secured to the lamp body concentric with said orifice, a reflector having a central opening, a reenforcing wall surrounding said opening and extending rearwardly from the reflector, said wall being adapted for detachable threaded engagement with said spacing frame whereby said reflector may be secured to and seated 25 against the front edge of said frame to bring the reflector opening in registration with said gas orifice.

30 2. The combination with a lamp body having a gas orifice, of an annular spacer frame secured at its rear edge to the body concentric with said orifice, a concave reflector having an opening, a reenforcing frame on said reflector concentric with said opening, a flange on said reenforcing frame, said flange 35 having threaded engagement with said spacer frame whereby to secure the reflector against the front edge of said frame with its opening in registration with the gas orifice.

35 3. The combination with a cylindrical 40 lamp body having a gas burner tube extending diametrically therefrom, an annular spacer frame intimately engaging at its rear edge against said body and secured thereto concentric with said tube, a reflector having an 45 opening for receiving said tube, and a flange 50 on said reflector concentric with said open-

ing, said frame and flange being threaded whereby said reflector may be secured to said frame to seat against the front edge thereof.

4. The combination with an irregularly shaped lamp body having a gas orifice, an annular spacer frame shaped at its rear edge to intimately fit said body and being permanently secured to the body concentric with said orifice, a concave reflector having an 55 opening, a reenforcing flange on said reflector at a distance from said opening but concentric therewith, and means for detachably securing said flange to said frame to hold the reflector rigidly seated against the 60 front edge of said frame with the reflector opening in registration with the gas orifice. 65

5. The combination with an irregularly shaped lamp body having a gas orifice, of an annular spacer frame shaped at its rear end 70 to intimately fit against said body and being rigidly secured to said body around said orifice, a reflector having an opening, a reenforcing frame secured to the reflector at a distance from said opening but concentric 75 therewith, a flange extending rearwardly from said reenforcing frame, said flange being threaded and said spacer frame being threaded to receive the flange whereby the reflector may be secured to the frame and seated against its front edge with the reflector opening in registration with the gas orifice.

6. The combination with an irregularly shaped lamp body having a gas burner tube 85 projecting laterally therefrom, of an annular internally threaded spacer frame shaped at its rear end to intimately fit against said body and being secured thereto concentric with said tube, a reflector having a central 90 opening, a reenforcing projection on the rear of said reflector spaced a distance from said opening but concentric therewith, external threads on said reenforcing projection for engaging with the threads of said spacer frame whereby said reflector may be detachably secured to said spacer frame against the front edge thereof and with its opening concentric with said burner tube. 95

In witness whereof, I hereunto subscribe 100 my name this 26th day of August, 1921.

WILLIAM J. FRISBIE.
